(57) CLAIM

The ornamental design for a double billed cap, as shown and described.

DESCRIPTION

FIG. 1 is a perspective view of a double billed cap,

FIG. 2 is a top plan view thereof,

FIG. 3 is a front elevation view thereof,

FIG. 4 is a back elevation view thereof,

FIG. 5 is a left side elevation view thereof; and,

FIG. 6 is a right side elevation view thereof.

The broken lines within the bounds of the claimed design represent stitching that does not form part of the claimed design.
